COVER FOR GOLF CLUB IRONS

Peter J. Damiani, 5835 N. Whipple St., Chicago, Ill., and Samuel G. Rita, 4024 W. Morse, Ave., Lincolnwood,
Ill.

Filed May 2, 1960, Ser. No. 60,420

Term of patent 7 years

(Cl. D34—5)

We claim:

The ornamental design for a cover for golf club irons, substantially as shown and described.
